UNITED STATES PATENT OFFICE.

WILLIAM HAWKS, OF CHICAGO, ILLINOIS.

DESIGN FOR A LAMP-FIXTURE.

SPECIFICATION forming part of Design No. 35,581, dated January 14, 1902.

Application filed September 16, 1901. Serial No. 75,625. Term of patent 3½ years.

To all whom it may concern:

Be it known that I, WILLIAM HAWKS, a citizen of the United States, and a resident of Chicago, in the county of Cook and State of Illinois, have invented and produced a new and original Design for a Lamp-Fixture, of which the following is a specification.

In the accompanying drawing the figure is a side view of a lamp-fixture embodying my design.

A lamp-fixture of my design comprises a substantially spherical reservoir 1, a tubular member 2, secured in the top thereof, arms 3, connected to the tubular member 2 closely adjacent to the reservoir 1, which diverge upwardly and have their upper ends bent inwardly toward each other, ornamental braces or brackets 4, which connect the reservoir 1 with the arms 3, and scrollwork 5, which ex-

tends upwardly from and connects the arms 3, adjacent to their free ends. The brackets 4 consist of scrolls, elements of each of which are disposed to form the figure shown at 6. The scroll 5 consists of symmetrical right and left hand sections which diverge downwardly from each other, elements of each of which are disposed to form the figure shown at 7.

I claim—

The design for a lamp-fixture, substantially as herein shown and described.

In testimony that I claim the foregoing as my invention I affix my signature, in presence of two subscribing witnesses, this 27th day of August, A. D. 1901.

WILLIAM HAWKS.

Witnesses:

H. H. ROUNTREE,
M. S. SOMERVILLE.
